UNITED STATES PATENT OFFICE.

HARRY A. SPILLER, OF BOSTON, MASSACHUSETTS, ASSIGNOR TO THE PNEUMATIC GUN CARRIAGE AND POWER COMPANY, OF WHEELING, WEST VIRGINIA.

MORTAR-CARRIAGE.

SPECIFICATION forming part of Letters Patent No. 480,215, dated August 2, 1892.

Application filed October 9, 1891. Serial No. 408,245. (No model.)

To all whom it may concern:

Be it known that I, HARRY A. SPILLER, a citizen of the United States, residing at Boston, in the county of Suffolk and State of Massachusetts, have invented certain new and useful Improvements in Mortar-Carriages; and I do hereby declare the following to be a full, clear, and exact description of the invention, such as will enable others skilled in the art to which it appertains to make and use the same.

This invention relates to improvements in the construction of mortar-carriages.

The object of the invention is to produce a mortar-carriage of great efficiency as a military arm, both offensive and defensive.

The object of the invention is, furthermore, to facilitate an easy and rapid operation in maneuvering the gun heretofore not obtained by any former construction.

The object of the invention is, furthermore, to obviate all lateral strains arising from the recoil of the gun by a system of pneumatic recoil-cylinders arranged in such manner that the resistance offered in taking up the recoil is always parallel to the longitudinal axis of the gun at all angles of fire.

The object of the invention is, furthermore, to produce a construction whereby the gun is returned into battery by the same system that takes up the recoil, one system acting in both operations, without assistance of auxiliary cylinders and springs as are now in use.

The object of the invention is, furthermore, to simplify the construction, thereby reducing the liability of derangement of parts and also reducing the cost of manufacture.

With these objects in view the invention consists of a mortar-carriage comprising a racer-plate secured to the foundation, on which travels a live roller-ring supporting the bed-plate.

The invention consists, furthermore, of a bed-plate provided with pillars or stays which form bearings for a series of centralizing guide-rollers, thus obviating the necessity of a central pivot.

The invention consists, furthermore, of a circular bed-plate supporting the cheeks of the carriage, which are suitably secured in

position thereon, being further supported by a front transom, which is also secured to the bed-plate.

The invention consists, furthermore, of a circular bed-plate supporting the cheeks of the carriage, which are provided with large trunnion-bearings for the reception of the trunnions formed on plates connecting in pairs the recoil-cylinders and are adapted to sustain the entire weight of the mortar, together with the mechanism for arresting the recoil.

The invention consists, furthermore, of a series of recoil-cylinders, in this instance shown cast in pairs, each pair connected by strong plates, which are provided with large trunnions fitting in bearings formed in the upper portion of the cheeks of the carriage and secured by bolts.

The invention consists, furthermore, of a series of recoil-cylinders which are arranged in pairs by connecting-plates and are provided with ways between the cylinders in which blocks or slides (having cross-heads in which the ends of the piston-rods are secured) are designed to work, and also trunnion-bearings for the reception of the trunnions of the gun, whereby it is supported and designed to operate in taking up the recoil.

The invention consists, furthermore, of a series of recoil-cylinders connected in pairs by plates which are secured by trunnions in the cheeks of the carriage, as above described, and are further provided with blocks or slides in which the gun is trunnioned, the slides having cross-heads at their forward ends, in which are secured the extreme ends of the hollow piston-rods by means of nuts, said rods extending rearward through suitably-packed glands in the heads of the recoil-cylinders, and provided with cylindrical valve-rods, whereby a portion of the air below the piston is admitted to the space above the head, for the purpose to be hereinafter described.

The invention consists, furthermore, of the above-described hollow piston-rods provided with chambered heads having suitable passages leading therefrom to the interior or forward end of the cylinder, which, in combination with the tapering valve-rods of the hollow pistons, at predetermined intervals or

when the gun is fired takes up the recoil by means of the cushion formed of compressed air and allows a sufficient amount to pass to the forward ends of the cylinders to nearly 5 form an equilibrium of pressure on both sides of the pistons, thereby taking up the counter-recoil and forming a positive elastic cushion by which the dead-weight of the guns is supported.

10 The invention consists, furthermore, of a series of recoil-cylinders provided with a system of pipes, which connect the cylinders and also a check-valve and cock in order to maintain an equilibrium of pressure and by which 15 they are supplied with air, said cylinders being trunnioned between the cheeks of the carriage, the trunnioned bearings of the gun in the slides adapted to work in the ways formed in the connecting-plates of the cylinders, the 20 slides provided with cross-heads extending forward and carrying the extreme ends of the piston-rods of the recoil-cylinders, and when the gun is fired a positive cushion is formed at the termination of the recoil, the air that 25 is displaced from under the pistons in their descent to the annular space on the other side of pistons forming a cushion for the counter-recoil of the gun.

10 The invention consists, furthermore, of 30 mechanism for elevating and depressing the gun, also for traversing the same, adapted to be controlled by means of hand-wheels, said hand-wheels to be in convenient reach of the gunner.

35 The invention consists, furthermore, of novel details of construction, whereby the objects of the invention are attained.

I have illustrated my invention in the accompanying drawings, in which—

40 Figure 1 is a side elevation, partly in section, of the gun and mount, the mortar being shown at sixty-five degrees, (65°), which is indicated by the index, and in dotted lines the mortar is shown in its recoil and loading 45 positions. Fig. 2 represents a plan view of the carriage, showing in dotted lines the gun in a horizontal position and the graduated scale and index for indicating the traverse of the carriage. Fig. 3 is a rear elevation, 50 partly in section, showing the construction and arrangement of parts forming the carriage. Fig. 4 is an enlarged detail sectional view of the mechanism for supporting and taking up the recoil of the gun and for elevating and depressing the same, and for the 55 supply and equalization of pressure of air in the pneumatic cylinders; and Fig. 5 is a detail sectional view on the line xx of Fig. 1.

In the drawings, A represents the sole or 60 racer plate, which is securely bolted to the foundation, upon which travels a live roller-ring A', adapted to support a circular bed-plate A². This bed-plate A² is provided with pillars or stays A³, which serve to stiffen the 65 plate, also, to form bearings for a series of centralizing rollers A⁴, which are held in place by means of headed pins or journals A⁵, se-

cured in the said pillars, thus obviating the necessity of a central pivot, thereby producing a compact construction which entails 70 less weight and reduces the cost of manufacture. The cheeks B B of the carriage are mounted upon and securely bolted to the bed-plate A², being further supported by a forward transom B'. In the upper portion of 75 the cheeks large trunnion-bearings B² are formed, and are provided with square caps b, as shown.

Arranged on each side of the gun is a series of pneumatic recoil-cylinders C C C C. In 80 this instance four are shown cast in pairs and connected by strong plates c, which are provided with large trunnions c', adapted to be supported in bearings B², formed in the upper portion of the cheeks B of the carriage, and 85 designed to support the entire weight of the gun and apparatus for arresting the recoil and also acting as the main pivot in elevating or depressing the gun, and are further secured in position by the nuts c². These plates c are 90 also provided with ways c³ for the reception of trunnion blocks or slides c⁴, in which the gun is mounted, and are provided at their forward ends with cross-heads c⁵, which confine the extreme ends of the piston-rods c⁶, which work 95 in the recoil-cylinders by means of the nuts c⁷. As these recoil-cylinders are of similar construction, a description of one will suffice to give a clear understanding of the device. A cylinder C, Fig. 4, is provided with a suitably packed gland c⁸ at its forward end, through which passes a hollow piston-rod c⁶, provided with a piston-head c⁹. A chamber c¹⁰ in the piston-head communicates with the forward portion of the cylinder through the openings c¹¹ 100 and with the rear portion by means of an opening c¹² in the piston-head coincident with the bore of the piston-rod, in which a tapering rod or valve D, having one end suitably secured in the rear head of the cylinder and the 105 other end adapted to work in the opening of the rod, as shown. In the drawings, Fig. 4, this rod D is shown of the same diameter at its extreme ends for the purpose of closing the communicating passage-ways between the 110 spaces on each side of the piston-head. As 115 the communicating air-passages c¹¹ between the cylindrical spaces on each side of the piston-heads c⁹ are opened by means of the descent of the pistons c⁶, a sufficient amount of 120 air passes from the lower to the upper ends of the cylinders to nearly form an equilibrium of pressure on both sides; but, owing to the differential areas of the two sides of the pistons, 125 the pressure on the lower sides is sufficient to run the gun into battery at all degrees of elevation required. As the pistons continue to descend, the air-passages are closed by the cylindrical rods D, thereby forming a positive elastic cushion for the purpose of arresting 130 the recoil; also, for supporting the dead-weight of the gun and accompanying mechanism.

E indicates a system of pipes connecting

the recoil-cylinders, in order to maintain an equilibrium of pressure and by which they are supplied with air.

E' is a check-valve and cock connecting 5 with the compressors that supply the air.

An elevating-band F is secured in position on the mortar in front of the trunnion-band by the bolts G.

H are elevating-racks, which are secured to 10 the under side of the recoil-cylinders C, engaging pinions H', mounted on a cross-shaft H², having bearings in the cheeks of the carriage. On the projecting end of this shaft outside of the carriage is mounted a friction 15 worm-gear H², which is operated by means of worm H³, shaft H⁴, and hand-wheel H⁵. Turning the hand-wheel in either direction causes the elevation or depression of the gun, and the number of degrees will be indicated 20 by the index-finger I on the dial I' on the side of the carriage.

Traversing the carriage is performed by means of the hand-wheel K, the motion of which is communicated to the carriage through 25 the medium of a shaft K', bevel-gears K², shaft K³, worm-gear K⁴, shaft and pinion K⁵, and circular rack K⁶, which is secured to the racer-plate A. The degrees of traverse are indicated by an index-finger L', traveling over a 30 circular graduated scale L², which is secured to the wall-plate L. The index-finger L' is attached to the circular bed-plate A², and is designed to indicate the length of movement.

To prevent the carriage from lifting when 35 the mortar is fired at a low angle, sustaining-clips M are employed, which engage an over-hanging flange M' of the racer-plate A.

To supply any deficiency of air in the recoil-cylinders, arising from slight leakages, a 40 small hand air-pump N is attached to the carriage.

The operation of the carriage is as follows: By the arrangement of parts herein shown and described, the recoil-cylinders C can be 45 supplied with compressed air at five hundred (500) pounds pressure, by hand-power, in thirty minutes with a portable air-compressor. Immediately following the completion of this step in the operation, the hand-wheel H⁵ is revolved, and through the train of gearing motion is communicated to the mortar, which is depressed into almost a horizontal position, in which position it is loaded. The gun being loaded, the hand-wheel H⁵, controlling the elevating mechanism, and hand-wheel K, controlling the traversing mechanism, are revolved, and the gun is trained to the desired position or angle of elevation, which will be indicated by the index-finger I when the gun is ready 50 for firing. After firing the recoil is taken up by the pneumatic recoil-cylinders and the gun automatically returned to battery, when the operation, as above described, is repeated.

In describing my invention I do not claim 65 the use of compressed air for taking up of the recoil and counter-recoil of the gun, as the idea is broadly covered by patent to James A.

Powlett, assignor to the Pneumatic Gun Carriage Company, No. 339,466, dated April 6, 1886.

70

Having thus fully described my invention, what I claim as new, and desire to secure by Letters Patent, is—

1. In a gun-mount, an all-round traverse, a circular bed-plate thereon, a carriage on the 75 bed-plate, and means operating independently of the traverse for centralizing the carriage on the said plate.

2. In a gun-mount, an all-round traverse, a circular bed-plate thereon, a carriage on the 80 bed-plate, and rollers operating independently of the traverse for centralizing the carriage on the said plate.

3. In a gun-mount, an all-round traverse, a circular bed-plate thereon, a carriage on the 85 bed-plate, and rollers carried by the bed-plate and operating independently of the traverse for centralizing the carriage thereon.

4. In a gun-mount having an all-round traverse, a circular bed plate or table, cheeks secured thereon and supporting in bearings the pneumatic recoil-cylinders, which are cast in pairs and arranged on each side of the gun, slide-blocks into which the gun is trunnioned, said slides adapted to work in ways formed 95 between the recoil-cylinders and provided with cross-heads, tubular piston-rods, chambered piston-heads having communicating passages, and a differential cylindrical valve, substantially as and for the purpose described. 100

5. In a gun-mount, an all-round traverse, a circular bed-plate having pillars or stays, a carriage on the bed-plate, and rollers in the pillars or stays for centralizing the carriage on the bed-plate. 105

6. In a gun-mount, a series of pneumatic recoil-cylinders arranged as described, slide-blocks working in ways between the recoil-cylinders, the elevating-band secured to the slide-blocks, mechanism for elevating and depressing the gun to be controlled by hand-wheels, and a system of tell-tales for indicating the elevation and traverse of the gun, substantially as set forth. 110

7. In a gun-mount, a series of pneumatic 115 recoil-cylinders arranged as described and provided with trunnions which are supported in bearings in the cheeks of the carriage, slide-blocks working in ways between said recoil-cylinders and into which the gun is trunnioned, the elevating-racks H, pinions H', friction worm-gear H², worm H³, shaft H⁴, and hand-wheel H⁵, substantially as described. 120

8. In a gun-mount, a series of pneumatic 125 recoil-cylinders arranged as described and provided with trunnions which are supported in bearings in the cheeks of the carriage, slide-blocks working in ways between said recoil-cylinders and into which the gun is trunnioned, the elevating mechanism and traversing rack K⁶, pinion K⁵, and worm-gear K⁴ on same shaft, worm K³, and bevel-gears K², shaft K', designed to be controlled by hand-wheel K, and a system of tell-tales for indicating the 130

angle of elevation and traverse of the gun, substantially as described.

9. In a gun-mount, an all-round traverse, a circular bed-plate thereon, and a carriage on the said plate having its cheeks provided with trunnion-bearings, in combination with a series of pneumatic cylinders arranged in pairs about the gun, said cylinders having trunnions engaging the trunnion-bearings.
10. A carriage and a gun trunnioned thereon, in combination with pneumatic recoil-cylinders arranged in pairs on each side of the gun

and trunnioned in the carriage-cheeks, mechanism connecting the cylinders with the gun, air-supply and equilibrium pipes communicating with the cylinders and with a suitable source of supply, and a check-valve for regulating the supply of air to the said pipes.

In testimony whereof I affix signature in presence of two witnesses.

HARRY A. SPILLER.
